UNITED STATES PATENT OFFICE.

FREDERICK W. STORCK, OF BOSTON, MASSACHUSETTS, ASSIGNOR, BY DIRECT AND MESNE ASSIGNMENTS, TO THE STANDARD STAMP AFFIXER COMPANY, OF SOMERVILLE, MASSACHUSETTS, A CORPORATION OF MASSACHUSETTS.

STAMP-AFFIXING MACHINE.

993,732.

Specification of Letters Patent. Patented May 30, 1911.

Application filed May 14, 1910. Serial No. 561,290.

To all whom it may concern:

Be it known that I, FREDERICK W. STORCK, a subject of the Emperor of Germany, residing at Boston, in the county of Suffolk and 5 State of Massachusetts, have invented a certain new and useful Improvement in Stamp-Affixing Machines, of which the following is a specification, reference being had therein to the accompanying drawings.

10 The invention relates to a machine for moistening and affixing stamps to envelops, postal cards or wrappers, or affixing the wrappers to labels or other flat surfaces, and is an improvement upon the machine shown 15 in an application filed by me March 25, 1910, Serial No. 551,528.

The invention relates especially to an improvement upon the feed for the stamp-strip or label-strip. In said prior application 20 the strip was fed by means of two cylindrical rolls between which the stamp-strip passed, and means were provided whereby the said feed-rolls at each period of movement moved through a predetermined arc 25 of movement, thus feeding the stamp-strip an exact predetermined distance at each period of movement. This distance of feed was supposed to be the exact length of a stamp. The stamps with which the device 30 is intended to be used come in long strips of a single stamp in width and coiled around a shaft, forming a roll from which the stamp-strip is unrolled in using the machine. Theoretically, the stamps are of an absolutely 35 uniform size, and the distance between the line of perforations which marks the tearing point of the stamp from the strip and the next following line of perforations which marks the dividing line from the next 40 following stamp is supposed to be uniform. If this were in fact the case, the feed mechanism of the device shown in the said previous patent application would work perfectly as the feed is absolutely uniform. It 45 is found in fact, however, that the distances between succeeding lines of perforations vary somewhat, and it sometimes happens that if a stamp-strip is being used in which the distances are slightly in excess of the 50 standard for which the machine is set that the projecting stamp is severed from the strip a little off of the intended line, and if this same variation continues through the strip so that there is a slight excess at each

feed, the variation will appear more and 55 more for each succeeding stamp, and after a while the stamp-strip will be severed so far from the proper dividing line as to spoil the stamps by cutting through the body thereof. 60

One feature of the invention relates to the construction of the feed in such form that the lines of perforations in the stamp-strip form a part of the feed.

Another feature of the invention relates 65 to a safety-device or take-up which will insure the stamp being properly positioned at every feed movement even if the stamps are improperly spaced.

Another feature of the invention relates 70 to the positive locking of the feed to prevent any backward movement or slipping of the feed during the operation of the device after the proper feeding movement is completed. 75

The invention will be fully understood from the following description taken in connection with the accompanying drawings, and the novel features are pointed out and clearly defined in the claims at the close of 80 the specification.

In the drawings.—Figure 1 is a side elevation, partly in section, of a machine embodying the invention, showing the machine with the stamp-strip passed around the feed-roll and in position to be fed forward for a stamp to be severed at the first stroke of the plunger. Fig. 2 is a sectional view through the case, showing the interior mechanism in side elevation, and showing an envelop fed 85 into position for stamping and the plunger partially depressed, and the stamp-strip fed forward for a portion of its full feeding movement, showing the method of feeding. Fig. 3 is an enlarged view of the feed mechanism in the position shown in Fig. 1. Fig. 4 is an enlarged view of the feed mechanism, showing the position corresponding to Fig. 2. Fig. 5 is a similar view to Fig. 4, showing the parts nearly at the end of 90 the feed movement, the folding line of the stamp-strip being engaged by the safety-positioning device. Fig. 6 is a section on line 6—6 of Fig. 1, showing the rear elevation of the feed mechanism. Fig. 7 is a section on 105 line 7—7 of Fig. 1, showing in plan the feed mechanism. Fig. 8 is a detail of the safety-positioning device and the feed-lock-

ing device. Fig. 9 is a section on line 9—9 of Fig. 1.

For the purpose of fully illustrating the invention, the parts shown in the previous application mentioned, except so far as they are modified by the present invention, are shown in the accompanying drawings and corresponding parts are similarly numbered, and will be briefly referred to.

10 1 represents the frame or case of the machine. A water-holder or reservoir 2 is provided having a top cover 3 formed with a trough or cup-shaped depression 4 in the bottom of which are one or more apertures 5 through which the water will rise in the cup recess 6 to the level that it stands in the holder 2. The envelops or cards to which the stamps are to be affixed are fed along on the level top surface of the cover 3, across 15 the top of the recess 6, to a position which will bring that portion of the envelop to which the stamp is to be affixed beneath the presser-plate 7 on the lower end of the plunger 8. As the envelop is pushed back 20 into position under the plunger, it passes under the pivoted fingers 11 mounted on shaft 12 which normally dip into the cup 6 and are lifted by the forward movement of the envelop under the fingers which thus 25 trail over the envelop and leave lines of water on the envelop. The correct forward 30 position of the envelop will be controlled by the forward end of the envelop striking against the stop 13. A side guide 19 guides 35 the side edge of the envelop so that it will feed in proper alinement.

The stamps 14 are in a long strip of a single stamp in width, and the strip is coiled around a shaft 15 forming a roll 16 inclosed 40 within a case 17, said case having a feed aperture 18 on the under side of sufficient width to allow the passage of the stamp-strip. Thence the strip passes down on the back-side of the feed-roll 20 in contact there- 45 with; thence under the feed-roll 20 on the plate 22 and forward above the cover 3 beneath the presser-plate 7. Preferably a guide-pin or roll 21 is provided under which the strip passes before it reaches the feed- 50 roll 20 in order to guide it. Said feed-roll 20 is mounted on a shaft 24. Instead of being cylindrical, as were the feed-rolls of said previous application, it is polygonal in cross- 55 section, preferably four-sided, forming a series of four edges 25 which successively engage the stamp-strip at each quarter turn of the feed-roll, the sides 27 of the feed-roll being preferably concaved to allow for the curl of the stamps, as shown, as the stamps 60 usually are slightly curled as the strip is run from the coil. The distance between two edges of the feed-roll is preferably equal to the distance between the lines of perforations of the shortest stamps.

65 Mounted fast on the shaft 24, which car-

ries the feed-roll 20, is a ratchet 26 formed with four teeth 30 spaced equally apart corresponding with the number of sides of the four-sided feed-roll 20, and so disposed that one of the teeth will come about midway 70 between the two corners of each side of the feed-roll 20. A pawl 31 is adapted to engage with the teeth 30 of the ratchet 26, said pawl being actuated by the downward movement of the plunger 8, as will be hereinafter described, so that in each downward stroke of the plunger, the ratchet will be moved through an arc equal to the distance between two teeth. That is, if there are four teeth, it will be moved through an arc of 80 ninety degrees, and the feed-roll 20 will be given a quarter of a rotation.

The plate 22, which supports the stamp-strip as it passes forward under the feed-roll 20, is pivoted at 28 in ears rising from 85 the stop 13 and is normally held up in contact with the feed-roll by a spring 29.

At each end of the feed-roll 20 on the shaft 24 and fast to the feed-roll 20 or made integral therewith, so as to move with said feed-roll, are two disks or heads 32 having four flat edges 33 which project outwardly at least as far as a straight line joining two adjacent corners 25 of the feed-roll so that if the feed-roll is laid on a flat surface, the 95 straight sides 33 will contact with the flat surface and the edges 25 may also rest on the flat surface. The preferable method of forming the feed-roll 20 and said disk or head portions 32 is to first form a rectangular bar or block with entirely flat faces and cut out the intermediate portions of each face between the two end portions which are left to serve as the disks 32, so as to form the concave or inwardly curved faces 27. 100 In this way, a plain surface laid flat upon the face 33 will contact with the edges 25 of the feed-roll. The corners of the disks 32 are beveled off, forming the beveled corners 34 so as to allow the feeding edges 25 of the feed-roll 20 to engage the stamp-strip against the plate 22 when the disk turns.

At each side of the pivoted plate 22 there is a rail 35, the two rails 35 being spaced apart sufficiently so that the space between them is equal to the length of the feed-roll 20, and the two opposite disks 32 are adapted to rest upon the rails 35. This leaves a thin space 36 between the upper surface of the plate 22 and the edges of the feed-roll 20 of a width equal to the length of the feed-roll and of the width of the stamp-strip through which the stamp-strip is threaded. When the feed-roll is at rest and the plunger is in the elevated position, as shown in Fig. 1, the two disks 32 will stand with one of the flat faces of each disk resting square upon the rails 35, and the stamp-strip is free to slide under the feed-roll in the space 36.

The stamp-strip is first threaded up 130

around over the back side of the feed-roll 20 and through the space 36 on the under side of the feed-disk forward on the plate 22 until the front edge of the forward 5 stamp is even with the edge of the plate 22, and in such position that the upper and lower rear edges 25 of the feed-roll will respectively engage one of the lines of perforations of the strip, the stamp being bowed 10 in slightly into the concave depression formed by the inwardly curved side 27 of the feed-roll if the width of the stamp is slightly greater than the length of the chord joining the said upper and lower edges 25 15 of the feed-roll. When the feed-roll 20 turns, the upper and lower rear edges 25, as viewed in Fig. 1, being in engagement respectively with the lines of perforations of the strip, the uppermost edge 25 of the feed-roll will 20 exert a pull on the stamp-strip, like a tooth, thereby pulling the strip down from the roll, and the engagement of the lower edge 25 with the line of perforations will feed forward the portion of the strip which is 25 beneath it correspondingly with the length which is pulled down from the coil; that is, during the quarter turn of the feed-roll, the stamp-strip will be fed forward a distance equal to the length of a single stamp. If, by 30 any chance, the stamps of the strip are of irregular or unusual length throughout the strip, or if any two successive lines of perforations happen to be of unusual distance apart, or if for any other reason the strip has 35 been insufficiently fed forward, so that there is a portion of the stamp under the feed-roll projecting slightly rearwardly of the feed-roll, as shown in Fig. 5, if the stamp-strip were left in this position, then the said irregularly fed stamp just spoken of, which 40 is beneath the feed-roll, will, when it is fed forward at a subsequent stage, be imperfectly positioned for the cutter to sever the stamp along the line of perforations, but it 45 will be cut a little back or forward thereof. For this reason, a compensating device, such as previously referred to, is employed. As already stated, the thin space 36 on the under side of the feed-roll is of sufficient depth 50 for the fairly loose play of the stamp, so that the stamp-strip may be moved backward or forward under the feed-roll. The compensating device referred to consists of a device which engages the crease or fold of 55 the stamp-strip along the line of perforations which projects to the rear of the feed-roll, if there is any such rearwardly projecting portion, and shoves it forward into exactly the right position as the feed-roll comes 60 to a rest. It is obvious that various forms of mechanical expedients may be employed for this purpose, the preferred form being that shown in the drawings and is as follows: A lever 70, pivoted at 71 to the frame 65 on the under side of the plate 22, projects upwardly and slightly rearwardly, having at its upper end a finger 72, preferably flexible, as for instance a flexible spring plate, which projects up somewhat above the plate 22 through a slot 73 therein so located that 70 when the feed-roll is in its position of rest at the end of a feed movement, the finger 72 will contact with the lower rear feeding edge 75 of the feed-roll or rather with the stamp-strip in contact with the feed-roll when there is a stamp-strip passing through. When the feed-roll is turning, as shown in Figs. 2 and 4, the edge 25 of the feed-roll will act as a cam to cause the plate 22 to turn down- 80 ward as it rides over it against the pressure of the spring 29, as will be seen from Figs. 2 and 4, and the engagement of the plate 22 with the lever 70 will turn the lever 70 back on its pivot until after the feed-roll has reached the center of its movement. During 85 the latter half of the movement of the feed-roll, the plate 22 will be rising under the pressure of the spring 29, and the spring 74, which is coiled around the pivot shaft 71, will cause the lever 70 and the presser-finger 90 72 to turn toward its normal position until at the end of the quarter turn of the feed-roll the finger 72 will again come up into its full forward position. In so doing, it will 95 engage the rearwardly projecting corner or fold 75 of the stamp-strip, as shown in Fig. 5, just before the feed-roll reaches the end of its forward movement and push the stamp-strip forward until the fold, which is along the line of perforations, comes up 100 against the lower rear feeding edge 25 of the feed-roll, thus properly positioning the stamp. The only possible variation which could then exist in the foremost stamp which projects beyond the front end of the plate 22 to be engaged by the cutter would be such 105 slight variation as would be due to a single stamp or combined variation of the stamps in front of the compensator 72 which in any event would be so slight as to be of no great 110 consequence. The device thus prevents the accumulation of variations through a long series of stamps.

The plunger 8 is formed with a bore 39 extending up from the lower end thereof within which is a coil spring 40, the lower end of which is seated upon a key or pin 41 which is mounted in the frame and rests upon the cheek-pieces 62, 63, the walls of the plunger being formed with vertical slots 115 42 on opposite sides thereof through which the key or pin 41 passes and thereby allowing vertical movement of the plunger 8. The slots 42 extend down to the lower end of the plunger 8 so that the plunger has a split end. The edge 51 of the presser-plate 7 forms a cutting or shearing edge in connection with the cutting edge 52 of the plate 22 to sever the stamps from the strip. The 120 presser-plate 7 is adjustably connected with 130

the plunger so that it may have a little adjustment in order that it may be properly adjusted with relation to the cutting edge 52 of the plate 22. This is fully shown and 5 described in said previous application and is shown and described here merely for the purpose of understanding the construction. The presser-plate 7 is formed with a dove-tailed groove in its upper side and the lower 10 end of the plunger 8 is formed with a dove-tailed tongue 64, the two tongues of the dove-tail being respectively on the two branches of the plunger which engage with said groove. Inserted in the lower end of 15 the plunger is a plug or block 65. Said block 65 has a screw-threaded hole passing transversely therethrough and one of the walls of the plunger 8 is formed with a hole to receive the head of the screw 67 which 20 passes through the threaded hole in the block and impinges against the opposite wall of the plunger. By turning the screw in one direction, the two walls of the plunger are spread, thereby tightening the 25 engagement of the tongue 64 with the groove way in the presser-plate 7 and by turning the screw in the other direction, the friction is diminished so that the presser-plate may be adjusted.

30 Projecting horizontally from the frame is a stud 43 to which is fulcrumed a bifurcated lever having two arms 44, 45, between which extends a roll 46 mounted on a stud 47 projecting from the side of the plunger. The 35 pawl 31 is pivoted at 48 on the lower end of the arm 45. The arms 44 and 45 form an inclined cam-way between them so that as the plunger 8 is depressed and the roll 46 carried thereby engages with the inclined 40 upper surface of the arm 45, the bifurcated lever formed by the arms 44, 45, will be turned on its pivot, moving the pawl 31 to the right from the position shown in Fig. 1, giving to the ratchet 26, and therefore to the 45 feed-roll 20, a quarter rotation.

It is important that the feed-roll 20 should not have any additional forward turn by its own momentum after the quarter turn for feeding the stamp; otherwise the 50 position of the stamp-strip will be disarranged. Such forward slip is not likely to occur, but I prefer to have a positive lock to prevent any such slip. Such a lock is provided as follows: Mounted fast on the 55 shaft 24 of the feed-roll, at the opposite end from the ratchet 26, is another ratchet 76 whose teeth 77 point in opposite direction to the teeth of the ratchet 26. Pivoted to the side of the frame or any suitable support, as at 78, is a dog 79 which is adapted 60 to engage with the teeth of the ratchet 76, the teeth of the ratchet 76 being so positioned with relation to the teeth of the ratchet 26 that as soon as the feed-roll has 65 reached the end of a forward feed movement,

the tooth of the dog 79 will engage with one of the teeth of the ratchet 76 and positively hold the ratchet 76 from any backward movement and consequently prevent any forward turn of the feed-roll 20. The dog 79 is formed with a horizontal slot located above the fulcrum 78 in which is loosely held a pin 80 whose inner end is seated upon a spring 81 which is under compression and holds the head of the pin back against the 75 wall of the case and tends also, by its expansion, to hold the forward end of the dog down with its tooth 82 in engagement with one of the teeth 77 of its ratchet. In order, however, to enable the feed-roll 20 to be 80 turned by the pawl 31, which engages with the ratchet 26, it is necessary that the dog 79 be disengaged from the tooth 77 before the feed can take place. For this reason, means are provided whereby when the 85 plunger 8 rises, after it has been pressed down to feed and affix a stamp, it will disengage the dog and hold it disengaged until the next downward movement. The means provided are as follows: On the under side 90 of the dog 79 is a downwardly projecting pin 83 which is engaged by the upper side of the presser-plate 7 just before the plunger 8 reaches the end of its return upward stroke, thereby slightly lifting the dog 79 95 sufficiently to disengage the tooth 82 from the tooth 77 of the ratchet. On the down stroke of the plunger, as soon as the plunger starts, the feed-roll will begin to move, carrying the tooth 77 of the ratchet 76 out 100 from under the tooth 82 of the dog 79 so that by the time the plunger has descended far enough for the dog to drop, the tooth 82 of the dog will be riding over the back of the tooth 77 in position to engage the next 105 following tooth 77 at the end of the forward feed of the roll under the actuation of the pawl 31 with the ratchet 26.

The feed-roll 20, as shown in the drawings and as described, is formed with four faces and the disks 32 are also described as formed with four corresponding flat faces 33 (disregarding the beveled corners 34) and, therefore, the driving mechanism is 110 constructed to give to the feed-roll a quarter turn at each stroke. It is found that the four-sided form is the most practicable. It is obvious, however, that the feed-roll might be constructed with either more or less than four sides and the disks 32 and the driving mechanism correspondingly modified, but in such case the feed-roll should be made of such size that each period of movement will feed the stamp-strip through a space equal to the length of a single stamp and in order to properly feed the strip, the edges of the faces should still be spaced apart sufficiently for two adjacent edges to engage with two adjacent lines of perforations. It is also obvious that the feed mechanism would oper- 115 120 125 130

ate with an unperforated strip because the feeding or engaging edges or corners of the feed-roll would contact with the strip with sufficient friction to cause the strip to feed, 5 although it is preferable to have the strip perforated or at least creased along the division lines, because the perforations or creases help the feeding. It is obvious also that it is not necessary for the said feeding 10 edges or corners 25 to contact with the stamp-strip throughout the whole width of the strip.

The operation of the device is as follows: The stamp-roll being mounted in its bearings in the case, the free end is unrolled sufficiently to thread it around under the feed-roll to the forward edge of the plate 22 so that the forward edge of the advance stamp will reach just to the cutting edge 52 of the 20 plate 22. The operator now pushes a letter in from the front on the plate 3 until the innermost end of the letter strikes against the stop 18. In so doing, it rides under the fingers 11 which leave lines of water upon the 25 envelop. When the envelop is positioned, the operator will press down upon the handle on the upper end of the plunger 8, forcing down the plunger, and the pawl 31 will cause the ratchet 26 and the feed-roll 20 to 30 move through a quarter turn and carry the stamp-strip forward the length of one stamp, bringing the outermost stamp out from the supporting-plate 22 beneath the presser-plate 7. The continued downward descent 35 of the plunger causes the cutting edge of the presser-plate, by its shearing action with the cutting edge 52, to separate the outermost stamp from the strip, and then presses it down upon the envelop, pressing the stamp thereon and spreading the threads of water 40 so that the stamp will be moistened and the pressure will cause the stamp to adhere to the envelop. During the rotation of the ratchet 26 and the feed-roll, the tooth of the 45 locking dog 79 will trail over the ratchet 76 and fall in behind one of the teeth 77 to lock it against further movement by its own momentum.

The device is adapted for use not only in 50 affixing postage stamps but for affixing stamps of any kind, meaning hereby to broadly include what are designated as labels and for convenience of designation and for the purpose of avoiding repetition the 55 words stamp and stamp-strip employed in the specification and claims are used in a broad sense as above mentioned.

What I claim is:

1. In a machine for affixing stamps which 60 are fed in a strip, a rotary feed roll polygonal in cross section, each face of the roll having two edges which are parallel with the axis of the roll, the angular edges formed by contiguous faces of the roll being spaced apart equal to the distance the strip is to be

fed for a single stamp, whereby two adjacent edges engage the strip lengthwise of two adjacent division lines and feed the strip.

2. In a device for affixing stamps which 70 are fed in a strip having lines of perforations between the successive stamps, a rotary feed roll, said feed roll being polygonal in cross section transversely of its axis, each face of the feed roll being of a length cross 75 sectionally of the axis equal to the distance between two adjacent division lines of the stamp strip, the angular edges formed at the junction of each face with its contiguous faces engaging with the strip along the division lines to feed the strip. 80

3. In a device for affixing stamps which are fed in a strip having lines of perforations between the successive stamps, a rotary feed roll, said feed roll being polygonal in 85 cross section transversely of its axis, each face of the feed roll being of a length cross sectionally of the axis equal to the distance between two adjacent division lines of the stamp strip, the angular edges formed at the 90 junction of each face with its contiguous faces engaging with the strip along the division lines to feed the strip and means for presenting the strip to the feed roll in such manner that two feed edges of the roll will 95 be in engagement with the strip along two adjacent division lines in feeding the strip.

4. In a device for affixing stamps which are fed in a strip having lines of perforations between the successive stamps, a rotary feed-roll, said feed-roll being polygonal in cross-section transversely of its axis, each face of the feed - roll having its opposite edges which are parallel with the axis adapted to engage two adjacent lines of perforations of the stamp strip which form the dividing lines between each stamp and the adjacent stamp, means for preventing the stamp strip to said feed-roll and means for actuating said feed-roll whereby the two opposite parallel edges of one of the faces of the feed-roll will engage two adjacent lines of perforations of the stamp strip at each period of movement of the feed-roll through an arc equal to that subtended by one face of 105 the feed-roll and feed the stamp strip the length of one stamp. 110

5. In a device for affixing stamps which are fed in a strip having dividing lines between the successive stamps, a rotary feed- 120 roll, said feed-roll being polygonal in cross-section transversely of its axis and having its faces inwardly curved viewed endwise of the feed - roll and with straight parallel edges longitudinally of the roll, each face of the feed-roll having its opposite edges which are parallel with the axis of the feed-roll adapted to engage two adjacent division lines of the stamp strip and means for rotating said feed-roll on its axis in a step-by- 125 130

step movement, whereby the stamp strip is fed by the engagement of said parallel edges of the feed-roll with two adjacent division lines of the stamp strip through a distance 5 equal to the length of a single stamp at each step-by-step movement.

6. In a device for affixing stamps which are fed in a strip having dividing lines between the successive stamps, a rotary feed-
10 roll, said feed-roll being polygonal in cross-section transversely of its axis and having its faces inwardly curved viewed endwise of the feed-roll and with straight parallel edges longitudinally of the roll, each face of the
15 feed-roll having its opposite edges which are parallel with the axis of the feed-roll adapted to engage two adjacent division lines of the stamp strip, means for rotating said feed-roll on its axis in a step-by-step movement and means for presenting said stamp strip to said feed-roll whereby the two opposite straight edges of one of the faces of the feed-roll will engage two adjacent division lines of the stamp strip at each period of
20 movement of the feed-roll through one of its steps of movement and feed the stamp-strip the length of one stamp.

7. In a device for affixing stamps which are fed in a strip, a rotary feed-roll polygonal in cross-section transversely of its axis, a supporting plate for the stamp-strip beneath the feed-roll along which the stamp-strip is fed between the feed-roll and said supporting-plate, the faces of said feed-roll being of
30 such width with relation to the stamps that two adjacent edges of the feed-roll parallel with the axis thereof are adapted to engage the stamp-strip along two adjacent dividing lines between the stamps and means for rotating the feed-roll whereby the two adjacent stamp-engaging edges of the feed-roll feed the stamp-strip.

8. In a machine for affixing stamps which are fed in a strip, a rotary feed-roll, means
40 for actuating the feed-roll through a predetermined arc of movement at each period of operation, said feed-roll having on its periphery feeding edges which are adapted to engage the stamp-strip along the lines of division between the stamps and feed the stamp-strip at each period of movement a distance equal to the length of a single stamp, and a movable compensating member which follows the fold of the stamp-strip
50 and forces it against the feeding edge of the feed-roll.

9. In a device for feeding a strip of stamps in a stamp affixing machine, a rotary feed-roll polygonal in cross-section through
60 its axis, a supporting-plate for the stamp-strip beneath the feed-roll having a way along which the stamp-strip may be fed between the feed-roll and said supporting-plate, the faces of said feed-roll being of
65 such width with relation to the stamps that

two adjacent edges of the feed-roll are adapted to engage the stamp-strip along the dividing lines between the stamps, means for rotating the feed-roll and causing the stamp-engaging edges of the feed-roll to feed the 70 stamp-strip and a movable compensating member which engages the rearwardly projecting fold of the stamp-strip during the movement of the feed and means for actuating said compensator whereby it forces the 75 said projecting fold of the stamp-strip forward in contact with the edge of the feed-roll.

10. In a device for feeding a strip of stamps in a stamp affixing machine, a rotary feed-roll polygonal in cross-section transversely of its axis, a supporting-plate for the stamp-strip beneath the feed-roll, the faces of said feed-roll being of such width with relation to the stamps that two adjacent edges of the feed-roll are adapted to engage the stamp-strip along the dividing line between the stamps, a polygonal head at each end of the feed-roll, rails on said supporting-plate spaced apart equal 80 to the distance between said heads and which form seats for said heads when the feed-roll is at rest, thereby forming a way for the stamp-strip between the feed-roll and the top of said supporting-plate of a 85 width equal to the distance between the rails, and means for rotating said feed-roll in a step-by-step movement, each period of movement being through an arc equal 90 to the arc subtended by one of the sides of the feed-roll.

11. In a device for feeding a strip of stamps in a stamp affixing machine, a rotary feed-roll polygonal in cross-section through its axis, a supporting-plate for the stamp-strip beneath the feed-roll, the faces of said feed-roll being of such width with relation to the stamps that two adjacent edges of the feed-roll are adapted to engage the stamp-strip along the dividing lines between the stamps, a polygonal head at each end of the feed-roll, rails on said supporting-plate spaced apart equal to the distance between said heads and which form seats for said heads when the feed-roll is at rest, thereby forming a way for the stamp-strip between the feed-roll and the top of said supporting-plate of a width 105 equal to the distance between the rails and means for rotating said feed-roll in a step-by-step movement, each period of movement being through an arc equal to the arc subtended by one of the sides of the feed-roll, said supporting-plate being pivoted at its forward end in front of the 110 feed-roll and being tilted by the engagement of the feeding edges of the feed-roll during its turning movement.

12. In a device for feeding a strip of stamps in a stamp affixing machine, a ro- 115

- 5 tary feed-roll polygonal in cross-section through its axis, a supporting-plate for the stamp-strip beneath the feed-roll, the faces of said feed-roll being of such width with relation to the stamps that two adjacent edges of the feed-roll are adapted to engage the stamp-strip along the dividing lines between the stamps, a polygonal head at each end of the feed-roll, rails on said 10 supporting-plate spaced apart equal to the distance between said heads and which form seats for said heads when the feed-roll is at rest, thereby forming a way for the stamp-strip between the feed-roll and the top of said supporting-plate of a width equal to the distance between the rails and means for rotating said feed-roll in a step-by-step movement, each period of movement being through an arc equal to the arc 15 subtended by one of the sides of the feed-roll, said supporting-plate being pivoted at its forward end in front of the feed-roll and being tilted by the engagement of the feeding edges of the feed-roll during its 20 turning movement, and means for holding the supporting-plate at all times in yielding engagement with the heads of the feed-roll.
13. In a device for feeding a strip of 25 stamps in a stamp affixing machine, a rotary feed-roll, a supporting plate for the stamp strip beneath the feed-roll, a polygonal head at each end of the feed-roll, rails on said supporting plate spaced apart equal to the distance between said heads and which form seats for said heads when the feed-roll is at rest thereby forming a way for the stamp strip between the feed-roll and the top of said supporting plate 30 of a width equal to the distance between the rails, and means for rotating said feed-roll in a step-by-step movement, each period of movement being through an arc equal to the arc subtended by one of the 35 sides of the heads of the feed-roll.
14. In a machine for affixing stamps which are fed in a strip, a rotary feed-roll which is adapted to engage the stamp-strip and feed the stamp-strip, a plunger, mechanism actuated by said plunger which engages said feed-roll and moves it through a predetermined arc of movement at each downward stroke of the plunger, thereby causing the feed-roll to feed the stamp-strip a distance equal to the length of a single stamp and locking mechanism controlled by the plunger which, when the plunger descends, is caused to become operative and lock the feed-roll against forward movement under its own momentum at the end of its positive forward feed.
15. In a machine for affixing stamps which are fed in a strip, a rotary feed-roll which is adapted to engage the stamp-strip and feed the stamp-strip, a plunger, mechanism actuated by said plunger which engages said feed-roll and moves it through a predetermined arc of movement at each downward stroke of the plunger, thereby causing the feed-roll to feed the stamp-strip a distance equal to the length of a single stamp and locking mechanism controlled by the plunger which, when the plunger descends, is caused to become operative and lock the feed-roll against forward movement under its own momentum at the end of its positive forward feed.
16. In a stamp affixing machine for feeding stamps in a strip having lines of perforations between successive stamps, a rotary feed-device having projections which are adapted to successively engage the lines of perforations in the stamp-strip, means for presenting the stamp-strip to the said feed mechanism, a plunger which is adapted to sever a stamp from a strip and press it upon an envelop, and mechanism connected with the feed-roll whereby the actuation of the plunger actuates the feed-roll whereby the projections on the feed-roll will engage with the lines of perforations in the stamp-strip and feed the stamp-strip.
17. In a machine for affixing stamps which are fed in a strip, means for engaging the strip at the division line between two adjoining stamps and feeding the strip through a predetermined distance at each operation, and a movable compensating member which forces the division line of the strip into engagement with the said feed mechanism.
18. In a machine for affixing stamps which are fed in a strip, means for intermittently feeding a stamp strip through a uniform distance, means for releasing the engagement of the feed with the stamp strip at the end of each period of movement thereby leaving the stamp strip free and a movable compensating member which engages the freed stamp strip on the division line between two unseparated stamps and is adapted to give to the stamp strip an additional forward movement if the stamp strip has been left by the feed with the division line back of a certain point.
19. In a machine for affixing stamps which are fed in a strip, a rotary stamp feed, means for actuating the stamp feed through a predetermined arc of movement at each period of operation, means for disengaging the stamp strip and the feed from each other at the end of each period of movement and a movable compensating member which engages the freed stamp strip on the division line between two unseparated stamps and causes it to move forward an ad-

ditional distance if the stamp strip has been left by the feed with said division line back of a certain point.

20. In a device for feeding a strip of stamps, a rotary feed roll, a supporting plate for the stamp strip beneath the feed roll, a polygonal head at each end of the feed roll, raised portions of said supporting plate which form seats for said heads when the feed roll is at rest thereby forming a channel for the stamp strip free from the feed roll.

21. In a device for feeding a strip of stamps, a rotary feed roll, a supporting plate for the stamp strip beneath the feed roll, a polygonal head at each end of the feed roll, raised portions of said supporting plate which form seats for said heads when the feed roll is at rest thereby forming a channel for the stamp strip free from the feed roll, and a movable compensating member which engages the stamp strip when free on the

division line between two stamps and gives to the stamp strip an additional forward movement if the stamp strip has been left by the feed with said division line back of a certain position.

22. In a device for feeding a strip of stamps, a rotary feed roll, a supporting plate for the stamp strip beneath the feed roll, a polygonal head at each end of the feed roll, raised portions of said supporting plate which form seats for said heads when the feed roll is at rest thereby forming a channel for the stamp strip free from the feed roll, said feed roll and said supporting plate having yielding movement of one with relation to the other.

In testimony whereof I affix my signature, in presence of two witnesses.

FREDERICK W. STORCK.
